UNITED STATES PATENT OFFICE.

LEROY MATTSON, OF OAKLAND, CALIFORNIA, ASSIGNOR TO LUCE-MATTSON ENGINE CO., OF SAN FRANCISCO, CALIFORNIA, A CORPORATION OF CALIFORNIA.

ENGINE.

Application filed May 11, 1926. Serial No. 108,213.

This invention relates to internal combustion engines of the two-cycle type shown in my co-pending applications Serial Nos. 80,915 and 83,798 filed January 13th and 5 26th respectively, 1926. Such an engine comprises one or more power cylinders with their cooperating pistons and a charging cylinder for each power cylinder. The charging cylinders are relatively large and 10 surround the inner portion of the power cylinders and the function of the charging cylinders is to supply explosive gas under pressure to the power cylinders. The gas initially enters the charging cylinders, where 15 it is compressed and forced into the power cylinders, from which it is expelled after the explosion thereof.

My invention herein relates to various improvements in this engine, which render the 20 construction thereof more practical and interchangeable and the operation more efficient.

One novel feature of the invention is to 25 provide mechanism for supplying a charge of air to the power cylinder just prior to the entry of the explosive charge thereto, this preliminary air charge acting to expel the burnt gases from the cylinder. This 30 method of injecting a stratum of air between the burnt gases and the new gas charge very efficiently expels the burnt gases with a great saving of gas and also functions to keep the cylinders clean.

Another novel feature of my invention 35 resides in forming the cylinders and the co-operating parts of the cylinder block in independent units and of different metals particularly adapted to serve their respective functions, the several parts being so constructed as to be readily assembled and each 40 part being interchangeable for making repairs and for other purposes hereinafter mentioned.

A further feature of the invention resides 45 in so arranging the gas supplying ports into the charging cylinder that a turbulent whirling action will be set up in the cylinder and thoroughly mix the gas therein and prevent condensation thereof.

50 It is the object of my invention herein to provide an improved engine embodying the several novel features above stated as well as other improvements which will herein-after appear.

55 In the accompanying drawings, I have

illustrated certain specific embodiments of my invention, but it will be understood that the invention can be otherwise embodied and that the drawings are not to be construed as defining or limiting the scope of the invention, the claim appended to the specification being relied upon for that purpose.

Referring to the figures of the drawing: Figure 1 is a vertical sectional view through my improved engine taken on line I—I of Fig. 2.

Figure 2 is a cross sectional view thereof taken on line II—II of Fig. 1.

Figure 3 is a fragmentary view similar to Fig. 1 and showing a modification thereof.

In the drawings, 1 indicates the lower half of the crank case on which is mounted the outer shell 2 of a cylinder block having its lower portion 3 forming the upper half of the crank case. The charging cylinder of 75 the engine is provided by a cylindrical member 4 fitting within the shell 2 and secured therein by bolts 5. The power cylinder is provided by a cylindrical member 6 having one end open and the other end closed, except 80 for a threaded hole for receiving a spark plug 7. An outside flange 8 on the member 6 rests on the shell 2 when the member is in place and is secured thereto by bolts 9. In such position, the open end of the cylinder 85 6 extends into the cylinder 4. A second shell 10 is removably carried on the first shell 2 and engages over and above the outer portion of the cylinder 6. The shell 10 may be secured to the shell 2 by bolts similar 90 to bolts 9. The chamber 11 within the shell 10 provides a water jacket about the cylinder 6.

It will therefore be seen that the cylinders 4 and 6 within which operate pistons 12 and 13 are constructed independently and are removably carried by the engine block. The advantages of such construction are numerous. One advantage resides in the fact that this arrangement permits the several parts to be made of different metal adapted to the particular parts. The wearing parts, as the cylinder members 4 and 6, may be made of strong wear-resisting material, while the non-wearing parts may be 105 made of a lighter material. I preferably make the cylinders of cast iron and the remaining engine block of aluminum or aluminum alloy, thus producing a durable light weight engine. The making of the 110

engine in sections also facilitates the accurate machining of the cylinder parts and permits the ready replacement of the cylinders and other parts with little cost.

5 While in Fig. 2 I have shown a two-power cylinder engine, it will be understood that my engine can be made with a power cylinder or as many power cylinders as desired. Each power piston 13 is connected with a 10 crank 14 on the shaft 15 by a connecting rod 16. Each charging piston 12 is connected to a pair of cranks on the shaft 15 by a pair of connecting rods 18, the crank 14 being substantially opposite the cranks 15.

15 17. Gas is provided to the charging cylinders 4 by means of a manifold 19 formed integral with the shell 2 and extending entirely around the cylinder. A carbureter connection is provided at 20. The shell 2 is slotted circumferentially at 21 and the cylinder is slotted longitudinally at 22 to provide ports between the manifold and cylinder. The slots 22 are formed in a direction 25 between lines extending radially and tangentially of the cylinder, whereby the gases passing therethrough to the cylinder set up a turbulent whirling action in the cylinder. This action thoroughly mixes the gases in 30 the cylinder and prevents condensation thereof. The making of the cylinder and shell in separate pieces makes the forming of these slots an easy matter. As shown in the drawing, the slots 22 are so located 35 that they are covered by the piston 12, except when the piston is in its lowermost position. Thus, a charge of gas can enter the cylinder through these ports only at the lower end of the piston movement.

40 40. It is well known that in two-cycle engines there is considerable inefficiency and a waste of gas in the displacing of the burnt gases by the incoming explosive charge. It is one object of my invention to provide an 45 improved construction wherein a charge of air is brought into the power cylinder ahead of the charge of gas in such a manner that the air acts to displace the burnt gases, thus making a great saving in gas and otherwise 50 facilitating the operation of the engine.

55 A member 23 mounted on the shell 2 provides a passage 24 from the manifold 19 to the upper end of the cylinder 4. A valve 25 in this passage is normally held closed by a spring 26. A passage chamber 27 is 60 provided in the shell 2 above the cylinder 4, this chamber being in communication with the cylinders 4 and 6 through ports 28 and 29. An air passage 30 is provided to the 65 chamber 27 and a valve 31 in this passage is normally held closed by a spring 32. Another passage 33 is provided from the chamber 27 into the chamber 6, this passage opening into the cylinder above the port 29. A 70 normally closed valve 34 controls the pass-

ing of air through the passage 33. An exhaust port 35 from the cylinder 6 is located diametrically opposite the ports 29 and 33 and slightly below the port 33.

70 It is essential that the valves 25 and 31 should open simultaneously and I provide the following connection to assure this action. A lever arm 36 pivoted at 37 has a yoke connection with the stem of the valve 25 at 38. A rod 39 connects the outer end of this lever with a lever 40 pivoted at 41. The other end of lever 40 has a yoke connection to the stem of valve 31. It will therefore be seen that when one of these valves opens the other must necessarily open.

75 Briefly, the operation of my engine as above described, is as follows. Considering that the charging piston 12 is just beginning its downward stroke and that the power piston 13 is beginning its upward stroke, the 80 piston 13 compresses the charge in its cylinder 6 preparatory to the explosion thereof. The downward movement of the piston 12 creates a vacuum in the cylinder 4, which 85 vacuum opens the valves 25 and 31. A charge of air is drawn into the chamber 27 through the passage 30 and a charge of gas is drawn into the cylinder 4 through the passage 24. When the piston 12 reaches a 90 position uncovering the ports 22, a full charge 95 of gas rushes in through such ports, the angular area of the ports causing this gas to set up a turbulent whirling action thoroughly mixing the charge and preventing condensation thereof.

95 Upon upward movement of the piston 12, the gas charge in the cylinder 4 and the air charge in the chamber 27 are compressed, the valves 25 and 31 closing automatically. The power stroke of the piston 13 occurs 100 during this compressing action. Downward movement of the piston 13 first uncovers the port 33 and air from the chamber 27 rushes into the cylinder 6 and displaces the burnt 105 gases through the exhaust port 35, this exhaust port being uncovered directly after the port 33. The port 29 is thereafter uncovered and a charge of gas forced into the cylinder 6. It will therefore be seen that a stratum of air has been forced into the cylinder 6 ahead of the gas in a manner displacing the burnt gases therein, thereby causing a great saving of gas and also operating to aid in thoroughly cleaning the cylinder of 110 burnt gases.

115 120 It may be desirable to open the valves 25 and 31 mechanically rather than to depend upon vacuum as in Fig. 1. In Fig. 3 I have shown an arrangement for performing this function, the parts of Fig. 3 corresponding to like parts in Fig. 1, being indicated by the same reference characters primed. A pair of cams 42 and 43 are carried on a cam shaft 44. The cam 42 operates a lever 45 pivoted at 46. A rod 47 connects this lever with a 125 130

lever 48. Levers 45 and 48 operate to open the valves 25' and 31' whenever the cam 42 functions. The cam 43 operates a lever 49 pivoted at 46 and a rod 50 connects this lever 5 with a lever 51 pivoted at 52 and having an arm 53 engaging the stem of valve 34'. The cam 43 therefore opens the valve 34' through these connections, the cams of course being arranged in the proper timed relation.

10 Having thus described my invention, what I claim is:

An internal combustion engine comprising the combination of a charging cylinder, a piston operating therein, a manifold extending about the cylinder and having a plurality of ports opening into the cylinder 15 therearound, the ports normally being closed by the piston which uncovers the same in its innermost position and the ports being inclined in a direction between the radial and 20 tangential whereby gases passing therethrough cause a turbulent whirling action in the cylinder, a smaller power cylinder co-operating with the charging cylinder, a piston operating in the power cylinder, means 25 providing a charging port from the charging cylinder to the power cylinder, and means independent of the charging cylinder for admitting air to the cylinder prior to the admission of a charge of gas through the 30 charging port.

LEROY MATTSON.
